[57] **CLAIM**

The ornamental design for a link unit for a conveyor chain link assembly, substantially as shown.

DESCRIPTION

FIG. 1 is a perspective view of a link unit for a conveyor chain link assembly showing my new design; FIG. 2 is a top plan view thereof;

FIG. 3 is a side elevational view thereof, the opposite side being a mirror image of the side shown herein;

FIG. 4 is a left end elevational view thereof;

FIG. 5 is a right end elevational view thereof; and

FIG. 6 is a bottom plan view thereof.
